UNITED STATES PATENT OFFICE

120,334

DESIGN FOR AN OLIVE OIL DECANTER

Joseph Mario Barolo, Detroit, Mich.

Application March 5, 1940, Serial No. 90,693

Term of patent 14 years

To all whom it may concern:

Be it known that I, Joseph Mario Barolo, a citizen of the United States of America, residing at Detroit, in the county of Wayne and State of Michigan, have invented a new, original, and ornamental Design for an Olive Oil Decanter, of which the following is a specification, reference being had to the accompanying drawing, forming part thereof.

In the drawing:

Fig. 1 is a front elevational view of an olive oil decanter, showing my new design;

Fig. 2 is a top plan view; and

Fig. 3 is a bottom plan view.

I claim:

The ornamental design for an olive oil decanter, as shown.

JOSEPH MARIO BAROLO.
